ABSTRACT

An ANFO explosive which is modified by the presence of small amounts of urea so that the explosive will not adversely react with pyrite in pyrite-bearing mines.

1 Claim, No Drawings

**UREA-MODIFIED AMMONIUM NITRATE-FUEL
OIL EXPLOSIVES**

This invention relates to prilled ammonium nitrate-fuel oil (ANFO) explosives.

Such explosives generally consist of the combination of prilled ammonium nitrate with about 5-10 percent of its weight of a liquid hydrocarbon such as fuel oil, kerosene, and the like. It has attained widespread use as a blasting agent in hard rock and metal mines. However, it cannot be safely employed in mines with relatively high temperature where significant pyritic minerals are present, e.g., copper-bearing ore bodies, because pyrite tends to react with the ANFO explosive, and causes fumes, fires or even initiates premature detonation. Bureau of Mines Report of Investigations No. 7187 discloses these problems.

We have now discovered a modified ANFO explosive which can safely be employed in the presence of pyrite and pyrite-bearing ores and minerals at much greater temperatures than heretofore. Generally, our invention comprises incorporating small quantities of urea in the ANFO explosive. This is not to be confused with the invention described in U.S. Pat. No. 3,447,982 wherein urea is added to ammonium nitrate if the ammonium nitrate is not porous enough to absorb at least 5 percent of its own weight of the oxidizable substance, e.g., liquid hydrocarbon. Our invention relates to the use of conventionally produced, sufficiently porous ammonium nitrate prills, e.g., wherein the prills are obtained by spraying a concentrate of solution into a prilling tower, and wherein the prills can absorb at least 5 percent of their own weight of the oxidizable substance.

It is therefore an object of the present invention to provide an ANFO explosive that does not adversely react with pyrite when dry or in contact with water or acid mine water.

Another object is to provide such an explosive that can be safely employed in the blasting of mines containing pyritic minerals.

Other objects and advantages will be obvious from the following more detailed description.

In the practice of the present invention, particulate urea, usually in powder form, is added to the prilled AN prior to the addition of fuel oil, or conversely may be added to the AN liquor prior to the prilling operation. Generally, it is incorporated in an amount of about 0.25 to 2.0 weight percent of the explosive composition, preferably in an amount of about 0.5 to 1.0 weight percent.

Thereafter, the ANFO manufactured from the urea-treated prills can be handled, loaded, and fired in identical fashion to untreated ANFO.

The following examples illustrate the effectiveness of the present invention.

EXAMPLE 1

Several 350 gram-samples were prepared of explosive compositions in admixture with 10 wt. pct. pyritic

ore, and subjected to simulated borehole tests to determine the temperature of incipient decomposition of the compositions. Some of the samples included water or acid solution which liquids often are present in boreholes. The results were as follows:

TABLE 1

	AN + ore		AN + 6 wt pct FO + ore			
	Dry	5 pct H ₂ O	5 pct acid ¹	Dry	5 pct H ₂ O	5 pct acid
Temperature (°F) of incipient decomposition						
A. No urea present	185	185	150	240	205	150
B. 0.5 wt pct urea	350	360	355	400	250	250

10 1 0.34 wt pct H₂SO₄ solution

EXAMPLE 2

20 A differential thermal analysis (DTA) was carried out in laboratory test tubes to closely observe the effects of urea addition. Several 5-gram samples were prepared of explosive compositions in admixture with 10 percent by weight of pyritic ore. Water or acid solution was included in some of the samples, and the results were as follows:

TABLE 2

AN + ore

	Dry	5 pct H ₂ O	5 pct acid	AN + 6 pct FO + ore + 5 pct acid
A. No. urea present	248-E	250-E	221-E	228-E
B. 0.5 wt pct urea	N	338-B	335-B	
C. 1.0 wt pct urea	N			340-B

30 E-sample ebullition with exotherm

B-sample ebullition without pronounced exotherm

N-no reaction; sample melted at 340° F

35 40 1/0.34 wt pct H₂SO₄ solution

As can be seen from these examples, the reaction between pyrite and ANFO is prevented, by the addition of urea, at temperatures up to the melting point of the ammonium nitrate. The use of ANFO prepared from AN-containing urea results in a decided improvement in the art of using ANFO to the extent that it is feasible to use ANFO in, for example pyritic-copper-ore-bodies where it has not hitherto been possible due to the high temperature present in the orebodies.

50 55 What is claimed is:

1. In an explosive consisting of prilled ammonium nitrate-fuel oil (ANFO), wherein said ammonium nitrate alone is porous enough to absorb at least 5 percent of its own weight of said fuel, the improvement of incorporating urea in said explosive in an amount of about 0.5 to 1.0 weight percent so as to elevate the temperature of incipient decomposition of said explosive when in contact with pyrite.
